UNITED STATES PATENT OFFICE

FREDERICK F. PFEFFERKORN, OF LAKEWOOD, OHIO, ASSIGNOR TO THE GEO. H. BOWMAN COMPANY, OF CLEVELAND, OHIO, A CORPORATION OF OHIO

DESIGN FOR A BIRD CAGE

Application filed May 9, 1929. Serial No. 31,159. Term of patent 14 years.

To all whom it may concern:

Be it known that I, FREDERICK F. PFEFFERKORN, a citizen of the United States, residing at Lakewood, in the county of Cuyahoga and State of Ohio, have invented a new, original, and ornamental Design for Bird Cages, of which the following is a specification, reference being had to the accompanying drawing, forming part thereof.

In said drawing, Fig. 1 is a front view of a bird cage, showing my new design; Fig. 2 is a side view thereof; Fig. 3 is a rear view thereof; Fig. 4 is a top plan view thereof; and Fig. 5 is a bottom plan view thereof.

I claim:

The ornamental design for a bird cage, as shown.

FREDERICK F. PFEFFERKORN.
